UNITED STATES PATENT OFFICE.

HOMER WORDEN, OF NEW YORK, N. Y.

DESIGN FOR A BOTTLE-CASE.

SPECIFICATION forming part of Design No. 32,186, dated February 6, 1900.

Application filed December 30, 1899. Serial No. 742,172. Term of patent 7 years.

To all whom it may concern:

Be it known that I, HOMER WORDEN, a citizen of the United States, residing in the city, county, and State of New York, have invented and produced a certain new and original Design for a Bottle-Case, of which the following is a specification.

This is a design for a bottle-case, and relates to the shape thereof.

The new design is shown in the accompanying drawing, which is a side elevation of a bottle-case embodying the new design.

Referring to the drawing, A is the lower part, B is the intermediate part, and C is the upper part, of the case embodying my new design. The part A has a smooth surface *a* approximately cylindrical at its upper extremity and flaring or conical at its lower extremity, where it terminates in a rough band *b*. At top the part A has a spiral band or convolution *c*. The part B has a middle portion *d*, consisting of a smooth surface approximately in the shape of a segment of a sphere, beneath which the part has an approximately cylindrical band or corrugations *e*. At its upper end the part B has a spiral and approximately cylindrical band of corrugations *f*. The part C is superposed on part B and has

a smooth surface *g* of less size than and of similar shape to the surface *a* to the part A, 30 being approximately cylindrical at top and flaring or conical at bottom. Beneath the surface *g* the part C has a band of spiral corrugations *h*, and above the surface *g* the part C has a roughened band *i*, consisting of a concave ring *j* and adjacent rings *k l*. Above the band *i* the part C has an approximately hemispherical dome *m*, which is surmounted by a tip *n*. The corrugations *c* and *e* and *f* and *h* correspond with and are adjacent to 40 each other, respectively.

The case embodying the new design has a distinctive and pleasing appearance. The successive surface bands *a*, *d*, and *g*, the dome *m*, and the intermediate bands are distinctive 45 features of my present design.

What I claim is—

The design for a bottle-case substantially as herein described and shown.

In witness whereof I have hereunto signed 50 my name in the presence of two subscribing witnesses.

HOMER WORDEN.
